UNITED STATES PATENT OFFICE

91,073

DESIGN FOR A COMBINATION BOTTLE PACKAGE

Earle H. Lackaye, New York, N. Y., assignor to
The Ault & Wiborg Company, New York, N. Y.,
a corporation of Ohio

Application July 7, 1933. Serial No. 48,656

Term of patent 14 years

To all whom it may concern:

Be it known that I, EARLE H. LACKAYE, a citizen of the United States, residing at New York, N. Y., have invented a new, original, and ornamental Design for a Combination Bottle Package, of which the following is a specification, reference being had to the accompanying drawing, forming a part thereof.

Figure 1 is an isometric view of the bottle package in closed position and Figure 2 is an iso-

metric view of the bottle package in open position and with the cover removed.

This article is usually sold as a unitary article, although the individual bottles may be separately removed from the box.

What I claim is:

The ornamental design for a combination bottle package as shown and described.

EARLE H. LACKAYE.
